UNITED STATES PATENT OFFICE.

ISIDOR K. TRAU, OF LOUISVILLE, KENTUCKY.

ADJUSTABLE CAP.

Application filed April 24, 1922. Serial No. 556,200.

To all whom it may concern:

Be it known that ISIDOR K. TRAU, citizen of the United States, residing at Louisville, in the county of Jefferson and State 5 of Kentucky, has invented certain new and useful Improvements in Adjustable Caps, of which the following is a specification.

This invention relates to wearing apparel and has special reference to the type of head 10 covering known as a cap.

More particularly the invention relates to an improvement over the prior invention of a cap for which application for Letters Patent was made January 18, 1922 under the Serial Number 530,121 and which has since matured into Letters Patent #1,414,797 dated May 2, 1922. The invention also relates to improvements in the cap shown in Reissue Patent #15,815, dated 20 April 8, 1924.

It has been found, in the practical construction of a cap in the manner shown in such prior invention, that certain objections exist which are due to the particular way 25 in which the upwardly extending slits are formed in the lower edge.

One important object of the invention is to improve this manner of forming the slits so as to overcome these existing objections.

It has also been found that the manner 30 of lining the cap is not altogether satisfactory.

A second important object of the invention is, therefore, to improve the manner of 35 lining the cap, especially at the slitted portions.

With the above and other objects in view, the invention consists in general of certain 40 novel details of construction and combinations of parts hereinafter fully described, illustrated in the accompanying drawings, and specifically claimed.

In the accompanying drawings, like 45 characters of reference indicate like parts in the several views, and:—

Figure 1 is a perspective view of the cap with the front portion shown raised in full lines and dropped onto the visor in dotted lines.

Figure 2 is a detail bottom view of the 50 cap.

Figure 3 is a detail exterior view of the cap showing a certain slit arrangement.

Figure 4 is a view similar to Figure 3 55 with the strap used with the cap turned back.

Figure 5 is a similar view showing the manner in which the lining folds.

Figure 6 is a side view of a modified form 60 of the device.

Figure 7 is a detail view of this modified form with the strap turned back.

Figure 8 is a section on the line 8—8 of Figure 6.

Figure 9 is a detail side elevation of a 65 second modification.

Figure 10 is a section on the line 10—10 on the Figure 9.

Figure 11 is a detail view on the second 70 modification on the Figure 7.

In the form here shown the body 10 of the cap is of the usual form and is provided with side seams 11 put to the rear of the visor 12. In front of the side seams the bottom edge of the cap extends considerably below the bottom edge to the rear of 75 said seams so that the lower front portion of said cap body is offset downwardly from the lower rear portion. The lower ends of the side seam stitchings terminate considerably above the bottom edge of the cap body to provide openings 13.

The top edge of the back portion 14 of a cap band is secured by stitching 15 to the lower edge of the rear body portion of the 80 cap and this band has forwardly extending ends 16 which pass over the visor and are adjustably connected in front of the body by the snap button arrangement 17 used in the prior device above referred to and 85 clearly described and disclosed therein.

Owing to the fact that the bottom edge of the front portion of the cap is below the edge to which the band is attached and that the visor is attached to the said front portion the band passes forward smoothly and without wrinkles. Moreover the band covers the lower parts of the side openings or slits 90 so that these are thus rendered invisible. It is to be noted that it is not essential that the openings be made at the lower ends of the side seams but this is a convenient place for the same and tends to economy of manufacture.

Within the cap is a lining 18 the lower 105 back edge of which is secured to the lower edge of the back portion of the band by stitching 19. At the slits or openings the lower part of this lining extends across said slits to cover or close the same on the inside 110 and it is sewed to the depending forward edges of the openings by stitching 20, being

also stitched to the bottom edge of the front portion of the cap body as at 21. It will be noted that the lining has a hem or doubled portion at its lower part, this hem terminating short of the inner and upper ends of the slits so that, upon contraction of the cap in adjustment to size, the folding or puckering of the hem is confined to the space below the said inner ends.

10 With this construction it will be noted that the soft lining is the only part of the bottom or band portion of the cap which at any time becomes folded or wrinkles and that the heavier cap band and bottom portions of the body are always smooth no matter how the size of the cap may be varied by the front adjustment.

In the forms shown in Figures 6 to 11 the body 10 of the cap is provided, with a 20 rear body portion 22 and a front body portion 23, these portions being defined from each other by a stitch line 24. At their lower parts the portions 22 and 23 are covered by a band 24' of the same construction 25 as the band 19 and the rear portion overlaps the front portion as at 25, said rear portion being securely stitched to the band by stitching 26. The cap is provided with the usual soft lining 27 which is secured to the front 30 portion by stitching 28 so as to leave a loose and foldable portion 29 behind the overlapping parts. It will be noted in this construction that at no time is there a gap on the side through which the lining is exposed, and that the rear ends of the front may come straight down as in Figure 6 or may be extended back as at 30 in Figure 9, in any event the lining forms a species of loose pocket at the inner side of such rear end.

40 There has thus been provided a simple and efficient device of the kind described and for the purposes specified.

It is obvious that minor changes may be made in the form and construction of the 45 invention without departing from the material principles thereof. It is not therefore desired to confine the invention to the exact form herein shown and described, but it is wished to include all such as properly 50 come within the scope claimed.

Having thus described the invention, what is claimed as new, is:—

1. A cap of the character described, having a body provided with slits extending upward from its bottom edge, the bottom edge portion of said body in front of said slits depending below the bottom edge portion of the body at the rear, a band having its middle portion stitched at its upper edge to the bottom edge of the rear portion of said body, a visor stitched to the bottom edge of the front portion of the body, said band having its ends extending forwardly over said slits, adjustable connecting means for the forward ends of said band, and a lining having its bottom edge stitched at the rear to the bottom edge of the band and at the front to the bottom edge of the body, said lining being further stitched to the material at the front edge of each slit in a line extending substantially parallel with said front edge, said lining extending continuous from front to back across the slits within the cap. 60

2. A cap of the character described, having a body provided with side seams open 70 at the bottom to form slits extending upward from its bottom edge, the bottom edge portion of said body in front of said slits depending below the bottom edge portion of the body at the rear, a band having its middle portion stitched at its upper edge to the bottom edge of the rear portion of said body, a visor stitched to the bottom edge of the front portion of the body, said band having its ends extending forwardly over said slits, 80 adjustable connecting means for the forward ends of said band, and a lining having its bottom edge stitched at the rear to the bottom edge of the band and at the front to the bottom edge of the body, said lining being further stitched to the front edge of each opening in a line extending substantially parallel with said front edge said lining extending continuous from front to back across the slits within the cap, said lining having a 85 doubled lower edge with the doubled portion below the upper ends of the slits. 90

In testimony whereof I affix my signature.

ISIDOR K. TRAU.
